UNITED STATES PATENT OFFICE.

FRANK D. HOWE, OF BROOKLYN, NEW YORK.

TRANSMITTING-GEAR.

SPECIFICATION forming part of Letters Patent No. 741,038, dated October 13, 1903.

Application filed May 21, 1902. Serial No. 108,312. (No model.)

To all whom it may concern:

Be it known that I, FRANK D. HOWE, a citizen of the United States, residing in the borough of Brooklyn, city of New York, and State of New York, have invented certain new and useful Improvements in Transmitting-Gears, of which the following is a specification, reference being had to the accompanying drawings, forming a part hereof.

10 This invention relates to power-transmitting devices in which by the interposition of gears between the driving and driven parts it is possible to vary at will the speed of the driven part. Although not limited to any 15 particular use, the invention is especially applicable to motor vehicles and cycles, and particularly to vehicles of this description wherein the power is transmitted through a shaft. It will be found capable, however, of 20 many different uses wherever a change of speed is desired from time to time.

The object of the present invention is to improve and simplify the construction of the gearing through which the power is transmitted and the changes in speed effected.

In the accompanying drawings, in which the improved gearing is illustrated, Figure 1 is a view in central section of the gearing with the driving-shaft in its central position. 30 Fig. 2 is a view in elevation of the end of the gear-casing through which the driving-shaft enters. Fig. 3 is a detail view of a portion of the ring on the end of the gear-casing for directing the movement of the driving member. Fig. 4 is a view, partly in central section and partly in side elevation, of a modified form of gearing embodying the invention, the controlling-lever being removed. Fig. 5 is a view in end elevation of the modification 40 shown in Fig. 4, the controlling-lever being shown, however.

In accordance with the invention a series of internal gears, each succeeding gear being larger than the one preceding, are coaxially mounted side by side. It will be obvious as the description proceeds that the precise number of internal gears which may be employed is immaterial so far as this invention is concerned, and in the particular 45 embodiment of the invention shown in Figs. 1 and 2, which will first be described, two such internal gears *a* and *b* are employed. These

two gears are secured to or made integral with the driven member *c*, with which they are also coaxial. A suitable casing *d* surrounds the gears *a* and *b*, and one end of the same is preferably made to terminate in a sleeve *e*, in which the shaft *c*, constituting the driven member, is carried and is capable of rotating. In the other end of the gear-casing, which is held stationary by lugs *z*, a carrier *f* is loosely fitted, so as to be capable of rotating in either direction, and the position of said carrier is such that its axis of rotation is eccentric with respect to the axis of the internal gears *a* and *b*. Said carrier is provided with a circumferential flange *g*, over which fits a ring *h*, which permits the rotation of the carrier, but holds the same from longitudinal displacement.

70 Mounted in the carrier *f* and having a longitudinal movement therein is a shaft *i*, constituting the driving member, its axis being eccentric though parallel with the axis of rotation of the carrier *f* and in one position of said carrier coinciding with the axis of the driven member. Said driving member comprises two parts secured together by a universally-jointed connection, (indicated at *y*), and on one part of the driving member *i* is 75 provided a pinion *j*, which is adapted to mesh with the internal gears *a* and *b*. Said pinion is preferably formed integral with the driving member *i*, which is recessed at *k* in order to fit the squared end *l* of the driven member 80 when it is desired to transmit power directly from one member to the other without the interposition of the gears *a* and *b*.

In order to shift the driving member to bring the pinion *j* into engagement with the driven member, either directly or through the internal gears *a* and *b*, any suitable means may be employed without departing from the present invention. The particular means shown in Figs. 1 and 2 comprises a rod *m*, 85 having a fork *n*, which engages the grooved end of a sleeve or bushing *o*. The latter forms a bearing-sleeve for the shaft *i* and is itself free to move longitudinally in the carrier *f*, but has no longitudinal movement with respect to the shaft. The rod is also provided with a pin *q*, which is loosely fitted in the carrier *f*. It will be evident that by giving the rod *m* a longitudinal and a twisting move-

ment the pinion j may be moved laterally to be brought into engagement with either of the internal gears a and b , or the recess in said pinion may be made to engage the squared 5 end of the driven member o . It will be noted, however, that some means should be provided to direct the movements of the driving member so that the engagements of the driving and driven members may be made with exactness. Accordingly the outer edge of the ring h is formed to constitute a curved track r for a lug x on the sleeve o . The curvature of this track is such that as the driving member is turned through an arc sufficient to 15 bring the pinion j into engagement with either of the internal gears the lug x , following the curvature of the track, will cause the necessary longitudinal movement of the driving member to bring it into registration with the 20 particular internal gear, and by inserting the lug x into the notches s' s^2 , &c., which are provided in said track for engagement by the lug x in order to hold the driving member from displacement in any desired position, 25 the pinion j is brought into exact registration with the particular gear. In order to reverse the rotation of the driven member, a pinion t is mounted so as to be in operative relation with gear b , and hence with the driven member on a spindle u , supported by the casing, and is adapted to be moved longitudinally by any suitable means to engage the gear b 30 and the pinion j .

When the driving member i is in direct engagement with the driven member c , the squared end l of the driven member rests in the recess k and the lug x engages the notch s' . When it is desired to decrease the speed of the driven member, a longitudinal movement is given the rod m sufficient to disengage the end l and lug x from their respective recesses and to move the pinion into the plane of the gear a , and then a twisting movement is given said rod, causing the carrier f 40 to rotate slightly, shifting the pinion laterally, and the lug x to follow upon track r . When the lug x reaches notch s^2 , it may be inserted therein, and the pinion j will then be in engagement with the internal gear a . In 45 a similar manner the pinion j may be brought into engagement with the gear b by giving the carrier a further longitudinal movement and a further twisting movement until the lug x engages the notch s^3 . In Fig. 2 the 50 broken lines a' and b' indicate the positions of the gears a and b , and the broken lines j' and j^2 the positions of the pinion j when said pinion is in engagement with gears a and b , respectively. In reversing the carrier is 55 shifted until the lug x engages notch s^4 , which movement brings the pinion j into the plane of the gear b , and pinion t is moved into the plane of gear b , and thereby engages both gear b and pinion j .

60 In the embodiment of the invention shown in Figs. 4 and 5 a single internal gear A is formed integral with the driven member C .

The driving member I , which, as before, is provided with a sleeve O and carries the pinion J , adapted to mesh with the internal gear A and recessed to fit the squared end L of the driven member, is mounted so as to be capable of longitudinal movement in a sliding carrier F , which is loosely secured to the end of the casing D by strips H H' , the latter 70 forming a track in which said carrier is capable of lateral movement. A hub or extended journal-bearing F' for the driving member is provided upon or formed integral with the carrier F . Pivoted on brackets Q , which are secured to said hub, is a controlling-lever M , having a sector N , the teeth of which mesh with a rack O' on the sleeve O . By rocking the lever M the driving member I is given the necessary longitudinal movement, and by applying a lateral pressure to said lever the carrier F is caused to slide in the track H H' . A guide-track R , having notches S' and S^2 , is provided, as before, for the lever M in order that said lever may be given the proper 80 movement to bring the pinion J into exact registration with a particular gear. 85

In order to reverse the rotation of the driven member, an external gear T is provided on and is thereby in operative relation with the 90 driven member, which gear is adapted to be engaged by the pinion J . A plurality of these external gears may, if desired, be provided upon the driven member, whereby 95 changes of speed may be effected substantially as such changes are effected through the series of internal gears described herein.

In the operation of the modified form of the gearing shown herein in Figs. 4 and 5 the controlling-lever M is guided by the track R , 100 and when said lever is inserted in the notch S' the pinion J will be in mesh with the internal gear A , the relative positions of said pinion and internal gear being shown by the broken lines J' and A' , respectively, in Fig. 105 5. When the controlling-lever is resting in the notch S^2 , the pinion J will be in mesh with the reversing external gear T , the relative positions of said external gear and pinion being shown when in this position by the broken 110 lines T' and J^2 , respectively, in Fig. 5. Besides the universally-jointed connection indicated at y , which connection is interposed between the two parts of the driving member to permit the latter to have the necessary lateral movement, a telescoping shaft may be used to permit the necessary longitudinal 115 movement of the driving member.

It is obvious from the foregoing description and operation of the improved gearing that it 120 is immaterial whether the driving member be moved to engage the driven member, or vice versa, and also that the relative positions of the gears and pinions may be reversed.

As the invention is now practiced the speed-changing device herein described is applied 125 as part of the driving mechanism on heavy motor trucks and vehicles of this description which are adapted to carry heavy loads. It

is found practicable to employ in such vehicles a series of internal gears to vary the speed ahead, and only one external gear is provided, inasmuch as one speed-reverse has been found to be all that is desired; but it will be obvious that if for any reason more than one speed-reverse should be demanded an adequate number of external gears might be added to meet such requirements.

10 I claim as my invention—

11 1. The combination with a two-part driving member, a driven member, and change-speed gears secured to the driven member, of a universal joint connecting the two parts of the driving member, a pinion secured to one of the parts of the driving member, a clutch member formed upon said pinion, a coöperating clutch member carried upon the driven member, and means to move the driving member to bring 20 said pinion into engagement with said gears or to effect the direct engagement of the driving and driven members through the clutch, substantially as set forth.

21 2. The combination with a two-part driving member, a driven member, and change-speed gears secured to the driven member, of a universal joint connecting the two parts of the driving member, a pinion secured to one of the parts of the driving member, a clutch member 30 formed upon said pinion, a coöperating clutch member carried upon the driven member, and a carrier in which said driving member is mounted whereby said pinion may be brought into engagement with said gears or the direct 35 engagement of the driving and driven members effected through the clutch, substantially as set forth.

36 3. A speed-changing and reversing mechanism comprising a driving member, a driven member, a primary speed connection between 40 said members, a change-speed gear secured to one of said members, a reversing-gear in operative relation with the same member, and a pinion secured to the other of said 45 members and capable of a longitudinal and a lateral movement to bring it in engagement with either of said gears.

46 4. A speed-changing and reversing mechanism comprising a driving member, a driven member, a primary speed connection between 50 said members, an internal change-speed gear secured to one of said members, a reversing-gear in operative relation with the same member, and a pinion secured to the other of said 55 members and capable of a longitudinal and a lateral movement to bring it in engagement with either of said gears.

56 5. A speed-changing and reversing mechanism comprising a driving member, a driven member, a primary speed connection between 60 said members, an internal change-speed gear secured to the driven member, a reversing-gear in operative relation with the driven member, and a pinion secured to the driving member, and capable of a longitudinal and a 65

lateral movement to bring it in engagement with either of said gears.

6. A speed-changing and reversing mechanism comprising a driving member, a driven member, a primary speed connection between 70 said members, an internal change-speed gear secured to one of said members, an external reversing-gear in operative relation with the same member, and a pinion secured to the other member and capable of a longitudinal 75 and a lateral movement to bring it in engagement with either of said gears.

7. A speed-changing and reversing mechanism comprising a driving member, a driven member, a primary speed connection between 80 said members, an internal change-speed gear secured to the driven member, an external reversing-gear secured to the same member, and a pinion secured to the driving member and capable of a longitudinal and a lateral 85 movement to bring it in engagement with either of said gears.

8. The combination with a driving member and a driven member of an internal gear secured to one of said members, an external 90 gear secured to the same member, and a pinion secured to the other member, one of said members being capable of a longitudinal and a lateral movement to bring said pinion into engagement with said gears. 95

9. The combination with a laterally and longitudinally movable driving member, and a driven member, of an internal gear secured to one of said members, an external gear secured to the same member, a pinion secured 100 to the other member, and means to move the driving member to bring said pinion into engagement with said gears.

10. The combination with a driving member, and a driven member, of an internal gear 105 secured to one of said members, an external gear secured to the same member, a pinion secured to the other member, one of said members comprising two parts, a universal joint uniting said parts, and means operatively connected with one of said members 110 to permit a longitudinal movement of that member, whereby said pinion and gears may be brought into engagement.

11. The combination with a driving member and a driven member, of an internal 115 change-speed gear secured to one of said members, an external gear coaxial with the first-named gear secured to the same member, and a pinion secured to the other member, one of said members being capable of a longitudinal and a lateral movement to bring said pinion into engagement with the gears. 120

12. The combination with a driving member, and a driven member, of an internal 125 change-speed gear secured to the driven member, an external gear coaxial with the first-named gear secured to the driven member, and a pinion secured to the driving member, said driving member being capable of a lon- 130

gitudinal and a lateral movement to bring said pinion into engagement with said gears.

13. The combination of a longitudinally-movable driving-shaft and change-speed mechanism, said mechanism comprising a driving member, a driven member, an internal change-speed gear secured to the driven member, an external change-speed gear secured to the driven member, a pinion secured to the driving member, a universal joint uniting said shaft and driving member, and means to move the driving member to bring said pinion into engagement with said gears.

14. The combination of a longitudinally-movable driving-shaft and change-speed mechanism, said mechanism comprising a driving member, a driven member, an internal change-speed gear secured to the driven member, an external change-speed gear secured to the driven member, a pinion secured to the driving member, a clutch member formed upon said pinion, a co-operating clutch member carried upon the driven member, a universal joint uniting said shaft and driving member, and means to move the driving member to bring said pinion into engagement with said gears or to effect the direct engagement of the driving and driven members through the clutch, substantially as described.

15. The combination with a driving member and a driven member of an internal gear secured to one of said members, an external gear secured to the same member, a pinion secured to the other member, and a laterally-movable carrier in which one of said members is loosely mounted and is capable of lon-

gitudinal movement therein, whereby said driving member and said driven member may be brought into operative relation.

16. A speed-changing and reversing mechanism, comprising a laterally and longitudinally movable driving member, a driven member, a primary speed connection between said members, a change-speed gear secured to the driven member, a reversing-gear in operative relation with the driven member, a pinion secured to the driving member, and means to move said driving member to bring said pinion into engagement with either of said gears.

17. A speed-changing and reversing mechanism, comprising a laterally and longitudinally movable driving member, a driven member, an internal gear secured to the driven member, an external gear secured to the driven member, a pinion secured to the driving member, and means to move said driving member to bring said pinion into engagement with either of said gears.

18. In a speed-changing gear, the combination with a driving-shaft, of a high-speed gear directly driven by said shaft, a low-speed gear consisting of a plurality of gear-wheels caused to engage by lateral and longitudinal shifting movements and means for producing rearward travel.

This specification signed and witnessed this 14th day of May, 1902.

FRANK D. HOWE.

In presence of—

ALBERT FIRTH,
BEATRICE I. FIRTH.
